SHAPED AMPLIFIER

John R. Boykin, Baltimore, Md., assignor to
Westinghouse Electric Corporation, East Pittsburgh, Pa., a corporation of Pennsylvania

Application April 1, 1944, Serial No. 529,109

4 Claims. (Cl. 179—171)

1

My invention relates to electronic amplifiers and, in particular, relates to the reduction in the ripple produced in the output current of such amplifiers by causes such as the effect of alternating heating current for the cathode, fluctuations of cathode emission and the like. It is particularly applicable to amplifiers having cathodes directly heated by alternating or pulsating current of a frequency greater than that impressed from the input circuit of the tube.

For certain purposes in the electronic art, it is desirable to use electron tubes having cathodes of what may be termed U-shape which are directly heated by alternating current. It is also known that such alternating-current heating tends to produce fluctuations of the output circuit current which may be referred to as "hum" which are naturally in undesirable interference with the action of the tube when it is used to amplify a signal input current. In the prior art, the magnitude of this hum has been greatly decreased by connecting the common terminal of the control-electrode circuit and the plate circuit to a point on the heater circuit which is at the mean value of the potential between the cathode terminals. This connection is usually made by attaching the control electrode and plate circuits to the midpoint of a resistor which spans the cathode terminals. It is also known that hum effects are produced by the magnetic field and the potential drop along the filament between the terminals of the cathode; and that by properly proportioning the magnitude of these effects, their resultant hum in the output circuit can be nearly eliminated.

However, it is frequently impracticable to make the point of attachment to the resistor spanning the cathode terminals at its exact electrical midpoint, and likewise impracticable in quantity production to produce tubes in which the other sources of hum above mentioned are ideally reduced to zero.

In accordance with my invention, however, I have found it possible to substantially eliminate the residual hum effects mentioned in the preceding paragraphs by the circuit connections shown in the drawing and about to be described.

One object of my invention is, accordingly, to provide circuit connections for an electronic amplifier having a cathode filament heated with alternating current which shall enable the tube to efficiently amplify fluctuating voltages impressed on its input circuit, while at the same time substantially eliminating the hum effects in its out-

2

put circuit which otherwise would be produced by the cathode heating current.

Another object of my invention is to provide a circuit for an electronic amplifier tube which shall make it possible to effectively amplify fluctuating currents impressed upon its input circuit while at the same time substantially eliminating fluctuations in its output circuit due to fluctuations of electron emissivity of its cathode.

Still another object of my invention is to provide a circuit for electronic amplifier tubes having cathode filaments directly heated by alternating current of a frequency greater than the voltage fluctuations impressed on their input circuits and which shall amplify the last-mentioned voltage fluctuations, while at the same time substantially eliminating the hum in their output currents which would normally be caused by their cathode heating currents.

Other objects of my invention will become apparent upon reading the following description, taken in connection with the single figure of drawing which illustrates a three-electrode electronic amplifier tube connected up with a circuit embodying the principles of my invention.

Referring in detail to the drawing, an electronic amplifier tube 1, which may be of the high-vacuum type and is shown here as embodying an anode 2, a control electrode 3 and a cathode 4, comprising a U-shaped electron-emissive filament 4 is supplied with alternating heating current from an alternating current source 5. To take one example, the frequency of the source 5 may be 800 cycles per second. The terminals of the filament 4 immediately outside the tube 1 are spanned by a resistor 6 having a tap 7 positioned as closely as possible to its electrical midpoint. An input transformer 8 impresses a fluctuating signal voltage which may, for example, have a frequency of 150 cycles per second in the control electrode 3 by means of its secondary winding 9, one terminal of which is connected to the control electrode 3 and its other terminal connected through a bias battery 11 to the above-mentioned tap 7. The anode 2 is connected through a resistor 12 to the positive terminal of a voltage source 13, of which the negative terminal is connected to the tap 7. A load may be supplied from the voltage drop across the resistor 12, preferably through a blocking condenser 14 in a manner too well known in the art to require further description here.

The flow of the alternating heating current through the cathode 4 will alternately make the 55 respective end terminals thereof positive and

negative relative to each other. However, the electrical midpoint of the filaments, being always half way in potential between those of the respective terminals, will remain fixed throughout the heating cycle at a value intermediate between them. If the tap point 7 is exactly at the electrical midpoint between the terminals of the cathode 4, it will likewise remain at the same fixed potential as the midpoint of the cathode itself, and under such circumstances, no voltage having the frequency of the supply 5 is effectively impressed between either the control electrode 3 or the anode 2 and the cathode 4. However, if the tap point 7 is displaced from the electrical midpoint of the resistor 6, a voltage having the frequency of the supply 5 can be shown to be impressed between both the control electrode 3 and the anode 2 and cathode 4. This will result in the production in the output resistor 12 of a current having the frequency of the source 5.

In accordance with my invention, I connect a capacitor 15 between the control electrode 3 and the anode 2. This, in effect, makes the tube 1 act like a reactance tube and interposes between the control electrode 3 and the cathode 4 an effective capacitance which is equal to μC , where C is the capacitance of the capacitor 15, and μ is the voltage amplification of the electron tube 1. The inductance of the secondary winding 9 is preferably tuned with this effective capacitance μC to resonate at the frequency impressed by the transformer 8; i. e. in the present example, is tuned to resonate at 150 cycles.

Under such circumstances, the secondary winding 9 and the capacitor 15 can be shown to constitute a low-pass filter of the L type for currents having the frequency of the supply source 5, and for any higher harmonics thereof. Because of the resonance to the frequency supplied through the transformer 8, the voltage fluctuations at that frequency of the control electrode 3 relative to the cathode 4 approximate a maximum. The impedance of the secondary winding 9 to currents of the frequency of the supply source 5 is, however, much larger than the effective impedance of the capacitor 15, so that the secondary winding 9 acts, in effect, to choke the flow of heating frequency currents through the capacitor 15 and the latter acts like a low-impedance shunt bypassing voltages of that frequency from the path between the control electrode 3 and the cathode 4.

It is evident, under such circumstances, that the capacitor 15 and inductance of winding 9 will act as an even more effective low-pass filter for any frequencies larger than those of the heating source 5, such, for example, as the second harmonic thereof which may be due to magnetic effects of the cathode heating current and to voltage drop along the cathode 4 between its terminals. The general statement may, in fact, be made that the winding 9 and the capacitor 15 will tend to choke out from the output circuit of the tube 1 any noise effects arising within the tube 1, such, for example, as those due to random fluctuations in electron emission from the cathode 4.

The arrangement of the capacitor 15 and the secondary winding 9 may be considered to constitute an inverse feed-back from the plate circuit to the grid circuit which tends to increase the stability and decrease distortion in the amplifier 1. This inverse feed-back will, in fact, tend to reduce the effect of disturbances in the plate circuit of the tube 1.

In accordance with the provisions of the patent statutes, I have described a particular embodiment of the principles of my invention, but these principles are obviously of broader application in ways which will be evident to those skilled in the art.

I claim as my invention:

1. In combination with an electron tube having an anode, at least one control electrode and an electron-emissive cathode, an inductive winding connected between said control electrode and said cathode, and a capacitor connected between said control electrode and said anode, the inductance of said winding being made such as to resonate at the frequency of input voltages impressed on said winding with μ times the capacitance of said capacitor, where μ is the voltage amplification of said tube.

20 2. In combination with an electron tube having an anode, at least one control electrode and an electron-emissive cathode, a circuit for heating said cathode from a source of periodic current, an inductive winding connected between said control electrode and a point on said circuit, an output circuit connected between said anode and the last-mentioned point, and a capacitor connected between said control electrode and said anode.

25 3. In combination with an electron tube having an anode, at least one control electrode and a cathode heated by periodic current of a predetermined frequency, an inductive winding connected between said control electrode and said cathode, means for impressing on said winding a periodic voltage which has a frequency lower than said predetermined frequency, an output circuit connecting said anode to said cathode, and a capacitor connected between said control electrode and said anode.

30 40 4. In combination with an electron tube having an anode, at least one control electrode and a cathode heated by periodic current of a predetermined frequency, an inductive winding connected between said control electrode and said cathode, means for impressing on said winding a periodic voltage which has a frequency lower than said predetermined frequency, an output circuit connecting said anode to said cathode, and a capacitor connected between said control electrode and said anode.

45 50 55 60 65 4. In combination with an electron tube having an anode, at least one control electrode and a cathode heated by periodic current of a predetermined frequency, an inductive winding connected between said control electrode and said cathode, means for impressing on said winding a periodic voltage which has a frequency lower than said predetermined frequency, an output circuit connecting said anode to said cathode, and a capacitor connected between said control electrode and said anode, the inductance of said winding being of such magnitude that it will resonate at said lower frequency with μ times the capacitance of said capacitor, where μ is the voltage amplification of said tube.
